UNITED STATES PATENT OFFICE

144,481

DESIGN FOR A JUICE EXTRACTOR

Raymond C. Casanov, Chicago, Ill.

Application September 21, 1945, Serial No. 122,221

Term of patent 7 years

(Cl. D89—1)

To all whom it may concern:

Be it known that I, Raymond C. Casanov, a citizen of the United States, and a resident of Chicago, in the county of Cook and State of Illinois, have invented a new, original, and ornamental Design for a Juice Extractor, of which the following is a specification, reference being had to the accompanying drawing, forming a part thereof, and in which:

Fig. 1 is a perspective view of the juice extractor embodying my design;

Fig. 2 is a perspective view similar to Fig. 1, showing the extractor in extended position;

Fig. 3 is a rear view of same;

Fig. 4 is a view similar to Fig. 3 showing the extractor in extended position; and

Fig. 5 is a plan view of the same.

I claim:

The ornamental design for a juice extractor, as shown.

RAYMOND C. CASANOV.
